UNITED STATES PATENT OFFICE.

JAMES KYLIÁNEK AND JOHN DOPYERA, OF LOS ANGELES, CALIFORNIA, ASSIGNEES
OF ONE-THIRD TO PAUL BERACKA, OF LOS ANGELES, CALIFORNIA.

CARTRIDGE-BELT.

1,183,572.

Specification of Letters Patent.

Patented May 16, 1916.

Application filed August 17, 1915. Serial No. 46,991.

To all whom it may concern:

Be it known that we, JAMES KYLIÁNEK and JOHN DOPYERA, subjects of the Emperor of Austria-Hungary, residing at Los Angeles, in the county of Los Angeles and State of California, have invented a new and useful Improvement in Cartridge-Belts, of which the following is a specification.

Our invention relates to cartridge belts and has for a primary object the provision of a device embodying a plurality of cartridge holding receptacles formed of a suitable water-proof material, such as metal, fiber or the like and provided with means for retaining the cartridges in position in the receptacles when not in use and means for ejecting them therefrom preparatory to using them.

A further object is to provide means for storing the cartridges in such a manner that they will be protected from the rain and for preventing the scratching or marring of the shells when they are being carried about in thickets or wooded country.

25 A further object is to provide means for rendering the upper ends or percussion ends of the cartridges visible for the purpose of selecting one of a desired size for use without removing it from the receptacle.

30 Other objects may appear in the description.

Referring to the drawings, in which similar characters of reference indicate the same parts throughout the several views, Figure 35 1 is a front view of the belt when stretched out the full length thereof showing the cartridge receptacles attached thereto; Fig. 2 is a plan of the same; Fig. 3 is an enlarged rear view in elevation of one of the receptacles; Fig. 4 is a sectional elevation of Fig. 3 showing a cartridge held therein and the means for ejecting them therefrom; Fig. 5 is a top plan of Fig. 4; Fig. 6 is a bottom plan of the same; Fig. 7 is a sectional plan of Fig. 3 on the line 7-7; Fig. 8 is a plan 40 showing a modified form of cartridge retaining means for the receptacles; and Fig. 9 is an elevation of Fig. 8, partly in section.

The belt 1, as shown in Figs. 1 and 2, may 50 be made of heavy canvas and provided with the leather straps 2 and 3 at opposite ends, the strap 2 carrying a buckle 4 by means of which it may be secured to the opposite strap 3 for holding the belt on the body of the huntsman, or, if desirable, the belt may

be made of leather or other suitable material and the straps omitted.

Tubular receptacles 5 are arranged at convenient intervals around and are secured to the belt 1 as hereinafter described, the receptacles being slightly longer than the cartridges 6 which slidably fit the interior thereof. Beads 7 are formed at the upper extremities of the tubes 5 and openings 8 are formed in the upper ends 8' thereof. A 65 piece of mica, glass, celluloid, or other transparent substance 9 is suitably held in the beaded end of each of the tubes and forms a closure therefor but permits the contents of the tubes to be exposed at all times to the view so that a selected cartridge may be removed therefrom, at will. A suitable gasket may be fitted into the beaded portion adjacent to the transparent end 9 in order that the tube may be perfectly water tight. 70 Springs 10 are secured at one of their ends in the beaded ends of the tubes and are compressible between the end 9 and the upper end of the cartridges 6 for the purpose of ejecting the cartridges, as hereinafter described. 75

The cartridges are retained in position in the tubes 5 against the tension of the springs 10 by means of flat springs 11 which are secured by means of rivets 12 to the walls of the tubes and within recesses 13 which are formed longitudinally of the tubes and are tapered from the bottom to the top. The lower ends of the springs 11 have shoulders 14 which are bent inwardly over and downwardly from the lower ends of the tubes 5, so that when the cartridges 6 are in position in the tubes, the shoulders 14 will engage the lower ends of the shells and thus firmly retain them in position in the tubes. 90

The tubes 5 are formed preferably of sheet metal and are rolled together at the ends, one end of the metal from which the tubes are formed having a pair of flat extensions 15 and the opposite having a single extension 16 which is central with regard to the extensions 15 on the opposite end and when the tubes are formed, engages the interval between them, as shown in Fig. 3. The ends of the metal in the formation of the tubes are drawn tightly together and are secured to the belt 1 by means of rivets 17 which extend through the holes 18 and washers 19 on the opposite side of the belt for preventing the wearing of the rivets therethrough. 100 105 110

A modified form of shell retaining means is shown in Figs. 8 and 9 which embraces a semi-circular spring clip 20 which is suitably riveted or otherwise suitably secured to the 5 wall of the tubes 5 at one end and the other or free end of the spring has a shoulder similar to that on the long spring 11, shown in Fig. 4, and serving the same purpose.

In the use of cartridge belts, the cartridges are generally held in a vertical position with the percussion ends uppermost, whereas in our device, we invert the shells so that in the ejecting operation, the discharge of the shells from their receptacles 15 will be assisted by gravity. The shells are forced upwardly in the tubes 5 against the tension of the springs 10, thus compressing these springs, until the lower ends of the shells snap into position beneath the clips 20 or shoulders 14 on the springs 11, and they are thus held in position until the springs are forced outwardly from over the ends of the shells, in which case the springs 10 promptly eject them from their tubes. 25 Inasmuch as the upper ends of the shells 6 are of heavy paper they are very susceptible to defacement by contact with snags, thistles, etc. when they are being carried through forests or underbrush, but in our 30 device the tubes 5 cover the entire shell and thus protect the shells from wear and rain, so that no difficulty may be encountered in forcing the shells into the gun barrel for use.

Having thus described our invention, what 35 we claim as new and desire Letters Patent for is:

1. A cartridge retaining means provided with a plurality of tubular receptacles for completely covering the cartridges to be held 40 thereby, said receptacles having transparent ends whereby the cartridges therein may be rendered visible for the selection of a desired size for use.

2. A cartridge belt provided with a plurality of rain-proof tubular cartridge receptacles having transparent closures for 45

rendering the cartridges in the receptacles visible for the purpose of selecting a desired size for use, cartridge retaining means and automatic cartridge ejecting means in each 50 of said receptacles.

3. A cartridge belt having in combination a plurality of cartridge holding receptacles extending the full length of the cartridges and for protecting them from rain and mutilation, means for effecting the visible selection of a cartridge of desired size without removal from the receptacles, and means for retaining the cartridges in and automatically ejecting them from said receptacles. 55

4. In a device of the character described, the combination of a belt, a plurality of cartridge holding receptacles independently secured to said belt and adapted to completely cover the cartridges, transparent ends in said 60 receptacles whereby the cartridges may be visibly selected for use, resilient cartridge retaining means and resilient cartridge ejecting means in said receptacles. 65

5. Cartridge retaining means including 70 tubular receptacles open at one of their ends and having transparent closures for the other ends thereof, and means for holding the cartridges in and ejecting the same from said receptacles, at will. 75

6. Cartridge holding means comprising tubular receptacles having transparent closures at the upper ends thereof for visibly selecting the cartridges for use and open lower ends for effecting the removal of the 80 cartridges therefrom, said cartridges being held in said receptacles against removal and capable of automatic ejection therefrom, at will.

Signed at Los Angeles, in the county of 85 Los Angeles and State of California, this 16 day of August, 1915.

JAMES KYLIÁNEK.
JOHN DOPYERA.

In the presence of—

CHARLIE M. STUDEBAKER,
RUDOLPH DOPYERA.
